[57] CLAIM

The ornamental design for a half chap leg covering, as shown and described.

DESCRIPTION

FIG. 1 is a lateral side elevational view of a half chap leg covering showing my new design;
FIG. 2 is a front elevational view;
FIG. 3 is a medial side elevational view;
FIG. 4 is a rear elevational view; and,
FIG. 5 is a view similar to FIG. 1 with the hook and loop fastening material partially open to expose the zipper.

FIG. 1

FIG. 2

FIG. 3

FIG. 4

FIG. 5
